(57) **ABSTRACT**

A device incorporates a light source, a power source, and a control unit. The device has two operating modes and a switch to select one of the two modes. In a first operating mode the light source has a first control function wherein it emits light and a second control function wherein it does not emit light. In a second mode the light source emits light when the sound of a gun firing pin is detected.

MASTER MODULE LIGHT SOURCE AND
TRAINERCROSS REFERENCE TO RELATED
APPLICATIONS

This application is a continuation in part of, and claims priority to U.S. application Ser. No. 14/459,274 entitled "MASTER MODULE LIGHT SOURCE, RETAINER AND KITS" filed on Aug. 13, 2014.

BACKGROUND OF THE INVENTION

There are many known devices used as laser sights for weapons, particularly pistols. It has, however, been difficult to develop a suitable laser sighter for small pistols (such as those that fit into one's pocket) because there is very little available space on the side or top of the gun to mount a laser, and mounting it to a trigger guard can be difficult plus the laser can be jarred out of position. Moreover, mounting a laser in any of the above positions on a small pistol may make the assembled pistol and laser hard to conceal, or fit within a pocketbook or pocket, which defeats its purpose.

Therefore, for these applications the laser has typically been mounted in a casing (preferably made of plastic) positioned in front of the trigger guard in order to minimize the additional size of the assembled device. The problem, however, is that for virtually every make and model of gun, a different laser assembly configuration is required because of the different gun configuration. Hence, a manufacturer may require to manufacture and inventory, and dealers may have to inventory, dozens (or more) of different laser assembly/casing units to fit each type of small pistol. This increases manufacturing and inventory carrying costs. Plus, there is a greater possibility that the manufacturer or dealer will have too much of one type of laser assembly/casing unit and not enough of another.

Additionally, there are laser sights used with a gun when firing bullets, and laser trainers, used with a gun when, instead of firing a bullet, when the firing pin is activated, a laser light beam is generated.

SUMMARY OF THE INVENTION

The present invention solves these and other problems by making one universal laser unit (also called a "master module") that incorporates a laser, a power source (such as one or more batteries), a control unit that controls the operation of the laser (which has one or more switches), and a laser adjustment mechanism, into one, fully-assembled, compact unit that can fit into any casing designed for virtually every type of small pistol. With this single laser unit (also called a "combination unit" or "unit"), a manufacturer and dealer only need to stock this single unit. Further, this unit is preferably attached using a single fastener to a casing that fits on a small pistol. In summary, a unit according to the invention greatly reduces assembly, manufacturing and inventory time and expense for the manufacturer, inventory expense for the dealer, and makes assembly easy for an end user (which is often the gun owner).

An example of the laser unit is shown in the appended drawings and some specific examples of the invention are set forth herein. In a preferred embodiment, a two-piece laser unit casing (preferably made of hard plastic), also called a combination unit casing, unit casing or casing, is provided. A fully-assembled laser unit according to the

2

invention is attached to one side of the casing, preferably by a single fastener, so mounting it is easy. The laser unit preferably is received in a cavity in the casing where it is supported and subject to limited shock and movement.

After the laser unit is attached to one side of the casing, the entire casing is assembled to a pistol. This is done in a manner known to those skilled in the art. The two pieces of the casing are pressed together and have a recess that receives the front part of the trigger guard. Once pressed together, the laser unit is held snugly in a cavity formed inside of the casing pieces, and the two pieces of the casing are fastened tightly together, such as by using two threaded fasteners with corresponding nuts. This pulls the two pieces of the casing together tightly on the front of the trigger guard, and the pieces also form a groove that mates against the bottom of the gun barrel in front of the trigger guard to help make a snug fit.

Once fully assembled onto a gun, the casing has an aperture for laser light to emanate out from the laser unit, two other openings to allow access to laser adjustment fasteners (one to adjust the laser in the up-and-down directions and the other to adjust it side to side), and an opening to provide access to a battery cap to allow the battery(ies) or other power source to be changed without opening the casing.

A laser unit according to the invention could be, for example, sold separately (with the casings also sold separately), could be sold assembled into a casing, or could be sold as a kit with multiple casings that fit multiple, different pistols.

In another aspect of the invention, a device incorporates a light source, a power source, and a control unit. The device has two operating modes and a switch to select between the two modes. In a first operating mode the light source has a first control function wherein it emits light and a second control function wherein it does not emit light. In a second mode the light source emits light when the sound of a gun firing pin is detected. This embodiment is not limited to any particular module structure, although the preferred structure is the master module described herein.

BRIEF DESCRIPTION OF THE DRAWINGS

FIG. 1 is an exploded view of a master module according to aspects of the invention.

FIGS. 2A-2F are views of a housing used in the master module of FIG. 1.

FIGS. 3A-3B are back and front views of a module mount board used in the master module of FIG. 1.

FIG. 4 is a back view of a circuit board used in the master module of FIG. 1.

FIG. 5 is a side view of the circuit board used in the master module of FIG. 1.

FIG. 6 is a front view of the circuit board used in the master module of FIG. 1.

FIG. 7 is a side view of a battery casing used in the master module of FIG. 1.

FIG. 8 is a cross-sectional, side view of a battery casing used in the master module of FIG. 1 showing internal threads.

FIG. 9 is a front view of a battery casing used in the master module of FIG. 1.

FIG. 10 is a rear view of a battery casing used in the master module of FIG. 1 with the battery casing attached to a connection plate.

FIG. 11 is a rear view of a battery cap used in the master module of FIG. 1.

FIG. 12 is a side, cross-sectional view of a battery cap used in the master module of FIG. 1.

FIG. 13 is a front view of a battery cap used in the master module of FIG. 1.

FIG. 14 shows a perspective, side view of a fully assembled master module according to aspects of the invention.

FIG. 15 is a front view of the master module of FIG. 14.

FIG. 16 is a side view of the master module of FIG. 14.

FIG. 17 is a back, perspective view of the master module of FIG. 14.

FIG. 18 is an opposite back, perspective view of the master module of FIG. 14.

FIG. 19 is a side, perspective view of the master module of FIG. 14.

FIG. 20 is a top view of the master module of FIG. 14.

FIG. 21 is a bottom view of the master module of FIG. 14.

FIG. 22 is another back, perspective view of the master module of FIG. 14.

FIG. 23 shows a master module according to aspects of the invention mounted in a casing that can be mounted to a picatinny rail of a gun.

FIG. 24 shows the opposite side of the structure of FIG. 23.

FIG. 25 shows a front, perspective view of the structure of FIGS. 23-24.

FIG. 26 shows a gun including a master module according to aspects of the invention.

FIG. 27 shows a close-up, partial view of the gun of FIG. 26 with the casing side removed to expose the master module.

FIG. 28 shows a side view of a casing including a master module according to the invention.

FIG. 29 is a side view of a gun including a casing having a master module in accordance with aspects of the invention.

FIG. 30 shows the opposite side of the gun of FIG. 29 with part of the casing removed.

FIG. 31 shows another gun with the casing open to show a master module according to aspects of the invention.

FIG. 32 shows one side of the gun of FIG. 31 including a casing with a master module in accordance with aspects of the invention.

FIG. 33 shows the opposite side of the gun in FIG. 32.

FIG. 34 shows a side view of an alternate gun with a casing open to show a master module in accordance with aspects of the invention.

FIG. 35 shows the gun of FIG. 34 with the casing enclosing the master module.

FIG. 36 is a schematic diagram of electronic components used to activate a light source when the sound of a firing pin is detected in accordance with aspects of the invention.

FIG. 37 shows printed traces on a first side of a module mount board for a sound-activated laser.

FIG. 38 shows printed traces on the second side of the module mount board of FIG. 37.

FIG. 39 is a schematic diagram of electronic components of a master module in accordance with aspects of the invention.

FIG. 40 shows printed traces on a first side of a module mount board of a master module in accordance with aspects of the invention.

FIG. 41 shows printed traces on the second side of the module mount board of FIG. 40.

FIG. 42 is a schematic diagram of electronic components of a master module in accordance with aspects of the invention.

FIG. 43 shows printed traces on a first side of a module mount board of a master module in accordance with aspects of the invention.

FIG. 44 shows printed traces on the second side of the module mount board of FIG. 43.

DETAILED DESCRIPTION OF PREFERRED EMBODIMENTS

10 Turning now to the drawings where the purpose is to describe preferred embodiments of the invention and not to limit same, FIG. 1 shows an exploded view of a laser module (also called a combined unit, or master module) 100. Combined unit 100 is configured to be compact and to provide a laser sighter for various types of small pistols. Combined unit 100 can reduce manufacturing and inventory costs because it can be used in place of multiple laser modules, each having different configurations.

Combined unit 100 has a laser module housing 1. Housing 20 1 is preferably made of metal, such as aluminum, or plastic, such as an electrically conductive plastic. Any suitable material, however, may be used to form laser module housing 1. Laser module housing 1 has a cavity 1A for receiving a module cushion ball 7 and laser module 8. Laser module housing has a top 1B, a first side 1C, a second side 1D, a bottom 1E (with portions 1E1, 1E2 and 1E3), a front 1F, and a back 11. Side 1C has apertures 1G for mounting housing 1 to module mount board 5.

The bottom 1E of laser module 1E is stepped with a first 30 part 1E1, a second part 1E2 and an angled end 1E3 that connects to side 11. Side 11 has an opening 1M through which laser light 1M through which laser light can be emitted.

Opening 1A leads to a cavity 1K that has a first portion 35 1KA and a second portion 1KB that retains module cushion ball 7. Bottom portion 1E1 includes an opening 1L that receives a set screw 9. Side 1D also includes an opening 1L that accepts a set screw 9. Side 1D also includes an opening 1L that accepts a set screw 9. When laser module 8 and cushion ball 7 are positioned in cavity 1K, set screws 9 can be tightened or loosened to reposition laser module 8 in cavity 1K.

Laser module 8 has a first end 8A that connects to PCB 55 in communication with opening 55B and a second end 8B that includes a lens through which laser light is emitted.

Module mount board 5 serves the purpose of being structural and including circuitry that directs power from power source 9 through circuit board 55 to laser module 8. Module mount board 5 has a rear side 5A and a front side 5B. A tactile dome switch 20 is attached to module mount board 5. Switch 20 has a compressive portion 20A (as shown it is on both sides 5A and 5B) that, when compressed, activates the circuitry to transfer power from power source 9 to laser module 8. When pressure is released from switch 20 preferably power is no longer transferred to laser module 8.

Module mount board 5 also includes openings 5C that align with openings 1G. Screws 22 are then positioned through openings 5C and received in openings 1G to retain module housing 1 to module mount board 5, and circuit board 55 is pressed into communication with the circuitry on module mount board 5 by contact 16 being in contact with contact 1G.

Battery casing 2 is tubular and hollow to receive insulating sleeve 4 and power source 9, which is shown is three batteries preferably of type 3V photo cell batteries. Sleeve 4 is positioned in the opening of battery casing 2 and batteries

9 are positioned inside of sleeve 4. Biasing spring 10 is positioned between batteries 9 and battery cap 3. Battery cap 3 has a threaded end 3A that is received in a threaded portion of the inner wall of battery casing 2, and an outer surface 3B with a slot 3D for being turned by a screwdriver.

FIGS. 2A-2F show various views of housing 1. FIGS. 3A and 3B show, respectively, the back surface 5BB and front surface 5CC of module mount board 5. Opening 7 is for receiving a fastener to connect combined unit 100 to a casing that mounts on a gun. FIGS. 4-6 show, respectively a back view, side view, and front view of circuit board 55.

FIG. 7 is a side view of battery casing 2 with a front end 2A through which insulation sleeve 4 and batteries 9 are inserted. Back end 2B includes a multiple (and preferably four) stems 2C to attach casing 2 to plate 2E, which is attached to module mount 5 utilizing openings 2F to be attached utilizing fasteners 5D. Threads 2D align with and receive threads 3A on cap 3.

FIGS. 11-13 depict cap 3. FIG. 11 is a rear view, FIG. 12 is a cross-sectional side view, and FIG. 13 is a front view with spring 10 pressed into cavity 3C.

FIGS. 14-22 show a fully assembled master module according to aspects of the invention.

FIGS. 23 and 24 show the fully assembled master module according to FIGS. 14-22 positioned in a casing 200 that can be mounted on picatinny rail of a pistol. FIG. 25 shows a perspective view of casing 200.

FIG. 23 shows a combined unit 100 positioned in a casing 200 that has a top portion configured to mount on the picatinny rail of a gun. In this view the casing 200 is open to show combined unit 100 therein. FIG. 24 shows the opposite side of the casing 200 with the casing closed. Fastener 208 is used to close the top portion snugly on a picatinny rail. 214 is an opening in canister 200 through which laser light can be emitted. FIG. 25 shows canister 200 in a side, perspective view. Rail 202, with groove 212A and rail 204, with groove 212B, can be tightened (using bolt 206 and nut 208) to a picatinny rail.

FIG. 23 shows a combined unit 100 positioned in a casing 200 that has a top portion configured to mount on the 200 picatinny rail of a gun. In this view the casing 200 is open to show combined unit 100 therein. FIG. 24 shows the opposite side of the casing 200 with the casing closed. Fastener 208 is used to close the top portion snugly on a picatinny rail. 214 is an opening in canister 200 through which laser light can be emitted. FIG. 25 shows canister 200 in a side, perspective view. Rail 202, with groove 212A and rail 204, with groove 212B, can be tightened (using bolt 206 and nut 208) to a picatinny rail. Fastener 218 helps retain module 100 in casing 200 and button 216 changes the condition of module 100.

FIG. 26 shows another canister configuration 300 for fitting a different gun 1000 that utilizes a combined unit 100. Gun 1000 has a trigger guard 1002, a grip 1004, and a top portion 1006. FIG. 27 is another canister 200' that is open to show the placement of combined unit 100 therein. FIG. 28 shows another canister 200' that utilizes a combined unit 100. FIGS. 29-30 show a gun 1050 having a trigger guard 1052, a grip 1054, and top portion 1056. Gun 1050 utilizes the canister 200' of FIG. 28 and combined unit 100.

FIGS. 31-33 show a gun 2000 with a canister 2010 including a combined unit 100 according to the invention. FIGS. 34-35 show a gun 3000 having a trigger guard 3002, a grip 3004, and a top portion 3006. A canister 3010 including a combined unit 100 according to the invention is retained in canister 3010.

FIG. 36 shows a circuit diagram and corresponding part listing for a combined unit 100 having a single, sound-activated mode. Combined unit 100 may be controlled by a microprocessor 70, for example a PIC10F204 microprocessor offered by MicroChip Corporation of Chandler, Ariz. A compact, omnidirectional microphone 72, for example an EM4013SMT microphone offered by Shenzhen Horn Audio Company, is connected to microprocessor 70. Responsive to detection of a particular acoustic signature received at microphone 72, such as the sound of the firing pin of a gun, microprocessor 70 activates laser module 8 to deliver a pulse of light, for example a pulse of approximately 100 milliseconds. In this manner, combined unit 100 may be utilized for training without the use of live ammunition. Microprocessor 70, microphone 72, and other components of combined unit 100 may be mechanically and electrically coupled to one another via module mount board 5 and the traces thereon illustrated in FIG. 37 and FIG. 38.

FIG. 40 shows a circuit diagram and corresponding part listing for another exemplary combined unit 100. In accordance with these aspects of the invention, combined unit 100 may be configured with multiple operational modes. In a first mode, combined unit 100 continuously activates laser module 8 responsive to a first configuration of a switch 20 (or multiple switches). In this manner, combined unit 100 may emit a continuous laser beam for targeting purposes. In a second operational mode, combined unit 100 activates laser module 8 for a limited duration pulse, responsive to a second configuration of a switch 20 (or multiple switches) and responsive to detection of a particular acoustic signature received at microphone 72. In this manner, combined unit 100 may be utilized to emit a pulse from laser module 8 only after detection of the sound of a firing pin. In other words, in accordance with these aspects of the invention a single combined unit 100 may be suitable for use as a targeting laser during live shooting, yet also suitable for training without live ammunition. Combined unit 100 may be toggled between operational modes via operation of switch 20.

In these aspects of the invention, combined unit 100 may utilize a microprocessor 70 having a higher pin count, for example a PIC12F1571 microprocessor offered by Micro-Chip Corporation. In this manner, microprocessor 70 may accommodate the control inputs from microphone 72 as well as switch(es) 20. Microprocessor 70, microphone 72, and other components of combined unit 100 may be mechanically and electrically coupled to one another via module mount board 5 and the traces thereon illustrated in FIG. 40 and FIG. 41.

FIG. 42 shows a circuit diagram and corresponding part listing for an exemplary combined unit 100 having a single, switch-activated mode. Microprocessor 70 and other components of combined unit 100 may be mechanically and electrically coupled to one another via module mount board 5 and the traces thereon illustrated in FIG. 43 and FIG. 44.

Some specific examples of the invention follows:

1. A combined unit for providing (a) a light source wherein the light source has a first control position wherein it emits light and a second control position wherein it does not emit light, (b) a power source, and (c) a control device to control the power provided to the light source, wherein the light source has a casing and is positioned in a block housing, the block housing having an opening aligning with a lens of the light source to enable light to be emitted outward from the block housing, and at least one surface to which at least part of the control device is mounted.

2. The unit of example 1 wherein the control device is a first circuit board and a second circuit board in electrical communication with the first circuit board.
3. The unit of example 2 wherein the second circuit board is at a right angle to the first circuit board.
4. The unit of either of examples 2 or 3 wherein the first circuit board has an electrical contact on an edge and the second circuit board has an electrical contact on an edge and the respective contacts touch to form an electrical connection when the unit is assembled.
5. The unit of example 4 wherein the electrical contacts are soldered together.
6. The unit of any of examples 2-5 wherein the second circuit board has a through bolt hole in communication with an end of the light source opposite its lens.
7. The unit of example 6 wherein the through bolt hole is plated.
8. The unit of example 7 or 8 wherein a spring is retained in the through bolt hole.
9. The unit of example 8 wherein the spring is soldered in the through bolt hole.
10. The unit of example 8 or 9 wherein the spring biases the light source away from the spring.
11. The unit of any of examples 8-10 wherein the spring provides a negative contact for the light source.
12. The unit of any of examples 1-11 wherein the block housing is comprised of a conductive material.
13. The unit of any of examples 2-11 wherein the second circuit board is connected to the block housing.
14. The unit of example 2 wherein the second circuit board is connected to the block housing by fasteners, the block housing is comprised of a conductive material and the fasteners provide a positive charge to the light source.
15. The unit of example 1 wherein power from the power source travels through the first circuit board to reach the light source.
16. The unit of example 15 wherein power from the power source travels through the first circuit board and second circuit board to reach the light source.
17. The unit of any of examples 1-16 wherein the light source is a laser.
18. The unit of any of examples 2-17 wherein the material block has at least two sides and the first circuit board is connected to one of the sides and the second circuit board is connected to another of the sides.
19. The unit of any of examples 1-18 wherein the power source is in a casing that is connected to the first circuit board.
20. The unit of any of examples 1-19 wherein the power source is one or more batteries.
21. The unit of any of examples 1-20 wherein the material block includes a plurality of openings that extend from an outside surface of the material block to the light source casing, wherein one opening aligns with the lens of the light source, and two of the openings are each configured to receive an adjustment device capable of moving the light source within the material block.
22. The unit of example 21 wherein each adjustment device is a set screw.
23. The unit of example 21 or 22 wherein one of the adjustment devices moves the light source from side to side and the other adjustment device moves the light source up and down.
24. The unit of any of examples 1-23 that is configured to cause the light source to operate in any of the following

- modes: stay constantly on, stay constantly off, blink, or turn from the on position to the off position after a predetermined period of time.
25. The unit of any of examples 1-24 that includes one or more switches to change the mode of operation of the light source.
26. The unit of example 25 wherein the one or more switches is on the first circuit board or the control device.
27. The unit of any of examples 2-26 wherein the first circuit board is attached to one side of the material block, the battery casing is attached to the first circuit board, and extends outward over a top of the material block.
- 10 28. The unit of any of examples 1-27 wherein the material block is comprised of a conductive material, such as aluminum, or an injection-molded conductive plastic.
- 15 29. The unit of any of examples 1-28 wherein the power source is three batteries.
30. The unit of any of examples 1-29 wherein the power source is enclosed in a casing.
- 20 31. The unit of any of examples 1-30 wherein the power source is surrounded by an insulating sleeve.
32. The unit of example 30 wherein the casing includes a cap on its end for removing and replacing the power source.
33. The unit of any of examples 1-32 wherein the light source has a first end through which light is emitted and the first end is retained in a module cushion ball inside the material block.
- 25 34. A unit casing mountable to a firearm, the casing including a cavity that receives and provides weather protection to a unit of any of examples 1-33.
- 30 35. The unit casing of example 34 that is formed of plastic.
36. The unit casing of example 34 or 35 that is formed in two pieces.
- 35 37. The unit casing of any of examples 34-36 that forms a channel that retains the front of a trigger guard of a gun.
38. The unit casing of any of examples 34-37 that, when assembled, has an opening that aligns with the lens on the light source to permit light to emit therefrom, has an opening to allow access to a side-to-side adjustment mechanism that adjusts the position of the light source, has an opening to allow access to an up-and-down adjustment mechanism that adjusts the position of the light source, and an opening to permit access to a battery cap, so that the power source may be removed and replaced.
- 40 39. The unit casing of any of examples 34-38 that is configured to fit on a part of a pistol between the front portion of the trigger guard and the lower surface of the barrel in front of the trigger guard.
- 40 40. A kit comprising a plurality of unit casings of different sizes and a combination unit of any of claims 1-33 that is not positioned in any unit casing, but is configured to be positioned in any one of the unit casings.
41. The kit of example 40 that has two unit casings.
42. The kit of example 40 that has one combination unit.
- 55 43. The kit of example 40 that has more than two unit casings and one combination unit.
44. The kit of example 40 that has more than two unit casings, and more than one combination unit wherein there are fewer combination units than unit casings.
- 60 45. The unit casing of any of examples 34-39 wherein the unit is attached to the casing by a single fastener.
46. The unit casing of example 45 that has two parts and the unit is attached to one of the two parts.
47. The kit of any of examples 40-44 wherein the unit is connected to the unit casing by a single fastener.
- 65 48. The unit casing of any of examples 34-39 or 45-46 that has a switch button on either side wherein each of the switch

buttons is in contact with a respective switch on the first circuit board or the control device.

49. The kit of any of examples 40-44 or 47 wherein each of the casings includes one long switch button and one short switch button wherein each switch button is configured to contact a respective switch on the combination unit when the casing is assembled with the combination unit inside.

50. The unit of example 2 or 3 wherein the second circuit board is in electrical communication with the block housing.

51. A casing including a combination unit of any of examples 1-33, the casing configured to fit on the picatinny rail of a gun.

52. The casing of example 1 that has two rail grasping members and a threaded fastener therebetween, the fastener capable of being tightened to pull the grasping members towards one another and tighten them to the picatinny rail.

53. The combined unit of example 1 wherein the control source is a plurality of circuit boards.

54. The combined unit of example 53 wherein each of the circuit boards is connected to the block housing.

55. The unit casing of any of examples 34-38, 45-46 or 48 that includes one long switch button and one short switch button wherein each switch button is configured to contact a respective switch on the combination unit when the casing is assembled with the combination unit inside.

Having thus described preferred embodiments of the invention, other variations and embodiments that do not depart from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result.

What is claimed is:

1. A device configured to fit inside of a casing that mounts under a barrel and in front of a trigger guard of a gun, the device including: (a) a light source having a first operating mode and a second operating mode, and a first switch to select either the first operating mode or the second operating mode, wherein when the light source is in the first operating mode it has a first control position wherein it emits light and a second control position wherein it does not emit light, and when the light source is in the second operating mode it emits light when it detects the sound of a gun firing pin, (b) a power source, (c) a control device to control the power provided to the light source; (d) wherein the control device is a first circuit board and a second circuit board in electrical communication with the first circuit board, and physically connected to the first circuit board; and (e) the light source is positioned in a block housing and the power source is one or more batteries positioned in a battery container, and the block housing and battery container are each physically connected to the second printed circuit board.

2. The device of claim 1, wherein the second circuit board is at a right angle to the first circuit board.

3. The device of claim 1, wherein the first circuit board has an electrical contact on an edge and the second circuit

board has an electrical contact on an edge and the respective contacts touch to form an electrical connection when the device is assembled.

4. The device of claim 3, wherein the electrical contacts are soldered together.

5. The device of claim 4, wherein the second circuit board has a through bolt hole in communication with an end of the light source opposite its lens.

6. The device of claim 5, wherein the through bolt hole is plated.

7. The device of claim 6, wherein a spring is retained in the through bolt hole.

8. The device of claim 7, wherein the spring is soldered in the through bolt hole.

9. The device of claim 7, wherein the spring biases the light source away from the spring.

10. The device of claim 7, wherein the spring provides a negative contact for the light source.

11. The device of claim 1, wherein the block housing is comprised of a conductive material.

12. The device of claim 1, wherein the first circuit board is physically connected to the block housing.

13. The device of claim 1, wherein the second circuit board is physically connected to the block housing by fasteners, the block housing is comprised of a conductive material and the fasteners provide a positive charge to the light source.

14. The device of claim 1, wherein power from the power source travels through the first circuit board to reach the light source.

15. The device of claim 14, wherein power from the power source travels through the first circuit board and second circuit board to reach the light source.

16. The device of claim 1, wherein the light source is a laser.

17. The device of claim 1, wherein the block housing has at least two sides and the first circuit board is connected to one of the sides and the second circuit board is connected to another of the sides.

18. The device of claim 1, wherein the light source has a casing and is positioned in a block housing, the block housing having an opening aligning with a lens of the light source to enable light to be emitted outward from the block housing, and at least one surface to which at least part of the control device is mounted.

19. The device of claim 1, wherein the battery container has a longitudinal axis, the light source is a laser module that has a longitudinal axis, wherein the longitudinal axis of the battery container is perpendicular to the longitudinal axis of the laser module.

20. The device of claim 1, wherein the first circuit board includes an opening through which light from the light source is projected.

21. A casing with the device of claim 1 mounted inside.

22. The device of claim 3, wherein solder forms at least part of the physical connection between the second circuit board and the first circuit board.

23. The device of claim 1, wherein solder forms at least part of the physical connection between the second circuit board and the first circuit board.
